UNITED STATES PATENT OFFICE

2,666,669

SINGLE INLET WHIRL CHAMBER NOZZLE

Fred W. Wahlin, Oak Park, Ill., assignor to
Spraying Systems Co., Bellwood, Ill., a corpora-
tion of Illinois

Application September 1, 1950, Serial No. 182,700

6 Claims. (Cl. 299—114)

1

My invention relates to nozzles for spraying liquids and has reference more particularly to such nozzles wherein a hollow conical spray is produced by imparting a whirling motion to the liquid before it passes through the discharge orifice.

In such nozzles it is customary to provide a so-called "whirl chamber" into which the liquid is introduced tangentially to impart rotation to the liquid in the chamber and the discharge orifice is located to lead from the whirl chamber at one end of the axis of rotation of the whirling liquid so that the liquid continues to whirl as it passes through the discharge opening.

It is important for uniformity of spray pattern that the whirling mass of liquid in the whirl chamber be oriented so as to rotate about an axis exactly aligned with the axis of the discharge orifice and that the supplied liquid be distributed uniformly around such axis and that such alignment and distribution conditions be unaffected by variations in the liquid pressure at which the nozzle is operated.

Nozzles with whirl chambers having a single tangential inlet have been employed theretofore with various expedients to counteract the unbalancing effect of introducing the liquid at one side of the whirl chamber, as, for example, in Baker Patent 2,141,077 wherein a spiral insert is provided in the whirl chamber or in Wahlin 1,938,000 wherein the whirl chamber is of convergent flat spiral form with inclined bottom, but such expedients have the disadvantage of excessive cost, inapplicability to simple and rapid machine production, lack of sufficient accuracy or practical limitations as to size, and accordingly, whirl chamber nozzles are generally made with a circular whirl chamber having two tangential inlets at opposite sides respectively thereof, or in some cases a plurality of such inlets spaced at equal intervals around the whirl chamber, in order to provide balanced or equalized inflow conditions which will not affect the accuracy of orientation or the uniformity of the whirling mass of liquid.

Two or more tangential inlets, however, are disadvantageous, especially in small capacity nozzles because of the small cross sectional size thereof that is necessary to cause the desired rapid rotation of the liquid in the whirl chamber. The rate of rotation of the whirling liquid depends upon the velocity of the inflowing liquid and as the two or more tangential inlets must have a total cross sectional area which is approximately the same as that of a single tangential inlet in order to provide the required inlet velocity, the size of the two or more inlets is oftentimes so small that they become clogged quite easily with the liquid that is being sprayed or by foreign particles therein.

The principal objects of my invention are to provide an improved whirl chamber nozzle with a single tangential inlet; to effectively counteract

2

the unbalance and lack of symmetry of the whirling mass which a single inlet tends to cause; to provide a construction which is simple and applicable to nozzles of any desired capacity and may be made readily and with precision in volume production; to permit convenient access to all parts for cleaning or replacement; and to utilize a composite whirl chamber and spray orifice member which is interchangeable to adapt 10 the nozzles for other capacities, these and other objects being accomplished as pointed out hereinafter and as shown in the accompanying drawing in which:

Fig. 1 is a side view of a nozzle embodying my 15 improvements;

Fig. 2 is an enlarged longitudinal sectional view of the nozzle of Fig. 1 taken on the line 2—2 thereof;

Fig. 3 is a transverse sectional view of the 20 nozzle taken on the line 3—3 of Fig. 2;

Fig. 4 is a fragmentary view of the upper end 25 of the nozzle tip retainer with part thereof in section on the line 4—4 of Fig. 2, and

Fig. 5 is an end view of the parts shown in 30 Fig. 4.

Referring now to the drawing, the spray nozzle as illustrated in Fig. 1 comprises a nozzle body 10, a nozzle body end member 11 which forms a continuation of the nozzle body, and a coupling ring 35 12 which serves to secure the end member 11 to the body 10. In said end member 11 is a spray tip or insert 13 through which the liquid is sprayed, said tip 13 having a whirl chamber 14 therein, a discharge orifice 15 at its upper end, and an external, peripheral rim 16 at its lower end. The whirl chamber 14 is cylindrical in shape with conical upper extension which tapers toward the discharge orifice 15 which is axially aligned with the whirl chamber 14.

The end member 11 has a cylindrical chamber 40 17 therein with an axially aligned opening 18 of reduced in diameter at one end in which the spray tip or insert 13 is secured, and internal threading 19 at the opposite end. Around its exterior

45 at the threaded end, the end member 11 is provided with a flange 20 which is adapted to be engaged by the clamping ring 12 for securing the end member to the end of the nozzle body 10 as shown in Fig. 2. At its other end the nozzle body 50 10 may be internally threaded for engagement with the externally threaded end of a liquid supply pipe 21 or it may be otherwise formed for liquid supply connection therewith.

The whirl chamber 14 is provided at its end 55 remote from the discharge orifice 15 with a relatively shallow circumferential enlargement 22 of circular shape and somewhat eccentrically disposed with respect to said whirl chamber 14 so that the axis of the said circumferential enlargement 22 is parallel but slightly off center with respect to the axis of the whirl chamber 14 and the orifice 15.

Between the eccentric enlargement 22 and the

3

cylindrical chamber 14 is an annular beveled face 35 of the shape of a frustum of a cone whose axis is concentric with the axis of the enlargement 22. Thus the bevel face 35 is of varying width with the greatest width at the side of greatest eccentric displacement of the enlargement 22 as shown in Fig. 2.

A liquid inlet 23 communicates tangentially with the circumferential enlargement 22 as shown in Fig. 3 at a place about a quarter turn before or in advance of the place of greatest radial width of said circumferential enlargement so that the entering liquid tends to flow around the enlargement in a relatively short circumferential portion thereof of gradually increasing radial width and thereafter continues such flow in a relatively long circumferential portion of gradual decreasing width, this arrangement having been found to accommodate and distribute the inflowing liquid without unbalancing the whirling mass of liquid or affecting the axial alignment thereof with the discharge orifice 15.

The tip 13 is held in place in the opening 18 of the end member 11 by means of a flat surfaced disk 24 which is clamped against the bottom end of said tip 13 and closes the lower open end of the whirl chamber 14. By reason of this open end construction of the nozzle tip 13 and closure thereof by the disk 24, the whirl chamber 14 with its conical upper end and with its eccentric enlargement or counter bore 22 and tapered annular face 35 may be readily and accurately formed in the tip 13 with ordinary machine tools or cutters and the tangential inlet 23 may be readily provided by cutting a groove with an appropriate milling cutter inasmuch as the open side of the groove is closed by the disk 24 when the nozzle is assembled.

The disk 24 is carried by a fitting 25 which has external threaded engagement with the internal threads 19 of the nozzle end member 11 for clamping the disk 24 against the bottom of the spray tip 13, the disk being tiltably secured on the end of said fitting 25 for adjustability to clamp flatwise against the lower or inner end of the spray tip 13 and insure complete closure of the open inner end of the spray tip 13. The latter has a gasket 33 therearound which is compressed between the spray tip rim 16 and the overhanging shoulder of the nozzle end member 11, as shown in Fig. 2, to seal the joint between said tip 13 and member 11, this compression of the gasket 33 being effected by the clamping of the disk 24 against the spray tip 13 by the fitting 25.

The outer end portion of the fitting 25 beyond its place of threaded engagement with the nozzle end member 11 is of reduced diameter to provide an annular chamber therearound, and the fitting 25 has a central opening 26 through which liquid is supplied to said annular chamber and therefrom through the tangential inlet 23 to the whirl chamber 14, said reduced outer end portion being diametrically slotted as at 31 to provide diametrical outlets from the central opening 26 to said annular chamber.

For securing the disk 24 to this reduced outer end portion of the fitting 25 said disk is provided on its underside with a central flared stem 31 which is inserted in the end of the central opening 26 of the fitting 25 and has the latter pressed or peened in therearound as at 28 to retain said stem therein but in a sufficiently loose manner to permit any necessary tilting of the disk 24 to bear exactly flatwise against the inner end of

5 the spray tip 13. The fitting 25 is slotted, as aforesaid, at the end thereof in which the stem 31 is secured and this slotting facilitates the pressing or peening in of the end of the fitting around the conical extension 31.

Preferably the fitting 25 is of a length to extend a substantial distance into the nozzle body to serve as a support for a cylindrical strainer screen 29 through which liquid is supplied to the central opening 26.

To this end said extended portion of the fitting 25 is provided with a series of annular shoulders 36 to support the cylindrical strainer 29 and with relatively wide annular grooves 37 between the shoulders 36, and at each groove 37 said extended portion is transversely slotted as at 38 to afford communication from the exterior of the strainer supporting extension to the central opening 26 therein.

Said opening 26 is closed at the end remote from the clamping disk 24 as indicated at 27 and the shoulder 36 at that end has an annular enlargement or rim 39 against which one end of the strainer 29 abuts and the other end of the strainer fits against a beveled face 40 within that end of the nozzle end member 11 which abuts against the nozzle body 10 as clearly shown in Fig. 2. Preferably the closed end of the strainer supporting portion of the fitting 25 has an external diametrical slot 34 for screw driver engagement for screwing the fitting 25 tightly in place.

If desired, the strainer and strainer supporting portion of the fitting 25 may be omitted and the latter may be in the form of a short threaded plug which terminates at the location indicated by the dotted line 41 in Fig. 2 with a screw driver slot 42 in that end and has the opening 26 leading directly into the interior of the nozzle body 10.

By reason of the above construction, all of the parts composing the nozzle may be made quite rapidly and with great precision using ordinary screw machine or similar processes and the nozzle is easily and quickly assembled and all the parts are readily accessible for cleaning or replacement.

Moreover, as the spray tip or insert 13 which includes the discharge orifice, whirl chamber and facilities for counteracting unbalance due to single tangential inlet is readily removable, the nozzle may be readily adapted to other spray capacity or volume by merely substituting a spray tip 13 of the desired volume or capacity.

Because of the single tangential inlet the nozzle is adapted to sprays of extremely low volume without likelihood of clogging and moreover in the event of clogging the tangential inlet 23 is readily accessible for cleaning especially because of its open sided groove form and closure of the open side by the removable clamping plate 24.

As a specific example of the above described nozzle, the discharge orifice 15 may be of .020 inch diameter and the whirl chamber 14 of $\frac{3}{16}$ inch diameter with the conical extension at the outer end thereof of 90° spread or 45° angle to the axis of the whirl chamber. At the bottom or lower end of the whirl chamber 14 the circumferential enlargement or counterbore 22 is of $\frac{1}{16}$ inch diameter and .015 inch depth and the annular bevel 35 is at an angle of 60° to the axis of the counterbore and concentric therewith, and the overall distance from the bottom or inner end face of the insert 13 to the top of the cylindrical portion 65 of the whirl chamber where it joins the conical

extension is $\frac{1}{8}$ inch. In this specific example, the tangential inlet 23 is .014 inch wide and .015 inch deep and the counterbore 22 is displaced eccentrically from the axis of the whirl chamber .002 inch toward the plane of the tangential inlet and .004 inch in the direction of inlet flow through said tangential inlet so that the greatest radial width of the circumferential chamber 22 is approximately 90° beyond the middle of the inner end opening of the tangential inlet 23 as shown in Fig. 3.

In this nozzle the liquid enters the interior of the nozzle body 10 through the pipe 21 or other liquid supply connection under the selected liquid pressure and passes through the screen 29 into the annular grooves 37 between the annular shoulders 36 and from these annular grooves through the slots 38 into the central opening 26 of the fitting 25. From this opening 25, the liquid passes through the slot openings 32 into the annular chamber around the reduced outer end of the fitting 25 and from this annular chamber is forced inwardly at high velocity through the tangential inlet 23 by the pressure of the liquid so as to produce a rapidly whirling mass of liquid in the whirl chamber 14 from which the liquid is discharged in a whirling stream through the discharge orifice 15.

While I have shown and described my invention in a preferred form, I am aware that changes can be made therein without departing from the spirit of my invention, the scope of which is to be determined by the appended claims.

What is claimed is:

1. A spray nozzle of the class described having therein a whirl chamber with a concentric discharge orifice leading therefrom at one end and an eccentric annular enlargement at the other end and closed at the side thereof remote from the whirl chamber, said whirl chamber having the surrounding wall thereof at the enlargement end thereof divergently sloped outwardly to the peripheral wall of the enlargement, and said peripheral wall having a single inlet opening therethrough and said opening leading tangentially into the annular enlargement approximately at the place of greatest eccentricity thereof.

2. A spray nozzle of the class described having therein a whirl chamber which has a concentric discharge orifice at one end and an eccentric annular enlargement at the other end and closed at the side thereof remote from the whirl chamber, said chamber having the surrounding wall thereof at the latter end divergently sloped outwardly toward the peripheral wall of and opening concentrically into the enlargement, said peripheral wall having a single inlet therethrough and said inlet leading tangentially into said annular enlargement approximately at the place of greatest eccentricity thereof.

3. A spray nozzle of the class described having therein a whirl chamber which has a concentric discharge orifice at one end and an eccentric annular enlargement at the other end, said chamber having the surrounding wall thereof at the orifice end convergently contracted toward the orifice and said chamber having the surrounding wall thereof at the annular enlargement end divergently sloped outwardly to the peripheral wall of and opening concentrically into the enlargement, said peripheral wall having a single inlet therethrough and said inlet leading tangentially into said annular enlargement approximately at the place of greatest eccentricity thereof.

4. A spray nozzle of the class described having therein a whirl chamber with a concentric discharge orifice leading therefrom at one end and a circular eccentric annular enlargement at the other end and closed at the side thereof remote from the whirl chamber, said whirl chamber having the surrounding wall thereof at the enlargement end thereof divergently sloped outwardly to the peripheral wall of and opening concentrically into the enlargement, and said peripheral wall having a single inlet opening therethrough and said opening leading tangentially into the annular enlargement approximately at the place of greatest eccentricity thereof said divergently sloped wall being of greatest width at the place of greatest eccentricity of said annular enlargement and of least width at the place of least eccentricity thereof.

5. A spray nozzle of the class described having therein a cylindrical whirl chamber which has a central discharge orifice at one end and an eccentric annular enlargement at the other end, a wall surrounding said eccentric enlargement and having a groove extending therethrough which leads tangentially into the eccentric enlargement approximately at the place of greatest eccentricity thereof, and a plate clamped against said wall and closing the open side of said groove and the enlargement at the side thereof remote from the whirl chamber, said whirl chamber having the discharge orifice end thereof conically tapered to the discharge orifice and said whirl chamber having the other end thereof conically flared to the eccentric annular enlargement, the conical taper at the discharge orifice end of the whirl chamber being concentric with the axis of the orifice and the conical flare at the eccentric annular enlargement end of the whirl chamber being concentric with the axis of the eccentric annular enlargement.

6. A spray nozzle of the class described having therein a whirl chamber which has at one end a discharge orifice leading therefrom and at the other end an eccentric annular enlargement which is closed at the side thereof remote from the whirl chamber and has a single inlet leading tangentially thereinto approximately at the place of greatest eccentricity thereof and provides an annular raceway in which the inflow from said tangential inlet is conducted circumferentially therearound, said raceway being of greatest radial depth at said place of greatest eccentricity and progressively diminishing in radial depth from said place circumferentially in the direction of inflow circulation around the raceway, and said raceway having therearound at the whirl chamber side thereof an annular overhanging wall which slopes convergently therefrom toward the discharge orifice end of the whirl chamber and is of a width along the raceway which varies with the radial depth of the raceway.
